UNITED STATES PATENT OFFICE.

THOMAS F. GROSSMAN, OF BROOKVILLE, PENNSYLVANIA.

FEEDER.

Application filed January 3, 1925. Serial No. 405.

This invention relates to a feeding device, the general object of the invention being to provide means for feeding a very small quantity of material from a receptacle containing the same so that this material can be mixed with other material.

Another object of the invention is to provide means for regulating the amount of material fed by the device.

10 While the invention is mainly designed for feeding bleaching material to flour it will of course be understood that the apparatus can be used for other purposes.

15 This invention also consists in certain other features of construction and in the combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:—

25 Figure 1 is an elevation of the improved apparatus.

Figure 2 is a longitudinal sectional view thereof.

30 Figure 3 is an enlarged sectional view through the drum or receptacle for containing the material to be fed.

Figure 4 is a detail sectional view through the drum.

35 Figure 5 is a view of one of the gates.

In these views, 1 indicates a supporting member which has the bearings 2 at its upper end for the horizontally arranged hollow shaft 3. A pulley 4 is connected with one end of said shaft so that the same can be rotated from any suitable source and a drum 5 is connected with the other end of the shaft. This drum is of substantially elliptical shape in cross section and has a circumferentially arranged rib 6 which has grooves 7 in its sides and perforations 8 are formed in the drum and pass through the center of said rib, these perforations permitting the material to pass from the

drum into a chute 8' which is supported by the extension 9 of the support 1. An opening 10 is formed at the center of the outer side face of the drum so that the material can be placed in the drum, this opening being closed by a cover 11.

In order to insure the passage of the material through the small perforations I place a presser foot 12 on an arm 13 which is secured to a shaft 14 by a set screw 15, said shaft passing through the hollow shaft 3 and having its end bent twice at right angles and secured to a projection 16 on the base or support 1 so that the shaft 14 is held against rotation. A spring 17 presses the enlarged end of the foot against the perforated part of the drum so that this part of the foot prevents clogging and insures the passage of the material through the perforations as the drum is being rotated. The parts are so set that the foot always engages that part of the drum which is lowermost so that the material passing through the perforations will drop into the chute and thus pass to the point where it will mix with the other material.

In order to regulate the amount of material fed from the drum I provide a plurality of gates 18, each gate being of channel shape so that it will embrace the rib with its extremities engaging the groove 7. Thus the gates are slidably mounted on the rib and can be manually adjusted to cover or uncover the perforations so that a number of perforations can be covered to cause the device to feed the correct amount of material.

With this invention a small amount of material is fed from the drum and by moving the gates the amount of material can be varied to suit conditions.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A device of the character described comprising a supporting base, a hollow shaft thereon, an elliptical shaped drum attached to one end of the shaft and having a plurality of circumferentially arranged perforations, a rib extending around the drum in alignment with the perforations, grooves on opposite sides of the rib, channel shaped gates embracing the rib and movable in said grooves, said gates adapted to be manually

moved over the rib to open and close said perforations, said gates being frictionally retained against accidental movement and a spring pressed foot supported by the shaft having engagement with the perforated part 15 of the drum to assure of passage through the perforations.

In testimony whereof I affix my signature.

THOMAS F. GROSSMAN.
